UNITED STATES PATENT OFFICE.

JOHN FRICK, OF NEW YORK, N. Y.

DESIGN FOR A BUTTON.

SPECIFICATION forming part of Design No. 18,687, dated October 16, 1868.

Application filed August 31, 1868. Serial No. 224,287. Term of patent 3½ years.

To all whom it may concern:

Be it known that I, JOHN FRICK, a citizen of the United States, residing at New York, in the county and State of New York, have invented and produced a new and original Design for Buttons, of which the following is a specification, reference being had to the accompanying drawings, forming part hereof.

Figure 1 is a face view of the top of the button, showing my design; and Fig. 2 is a side elevation of same, these two views being deemed necessary to fully illustrate my design.

The leading feature of my design consists in the figure of the Union flag displayed on a circular ground inclosed by a circular border having well-defined edges.

In the drawings, C designates the Union flag displayed upon the circular ground E, which is encompassed by the circular border D, having definite line edges B, the whole covering the outer face of the button A. The button is provided with the shank and head F.

What I claim is—

The design for a button herein shown and described, the same comprising the Union flag C, displayed on the circular ground E and encompassed by the circular border D, having line edges B, as set forth.

JOHN FRICK.
